METHOD OF AND APPARATUS FOR MAKING
BAGS AND THE LIKE

Adolph Potdevin, Garden City, and Paul Hunziker, Hamilton Beach, N. Y., assignors to Potdevin Machine Company, Brooklyn, N. Y., a corporation of New York

Application January 6, 1937, Serial No. 119,218

11 Claims. (Cl. 164—68)

This invention is directed to an improvement in bag making machines, and has for one of its objects the provision of a bag making machine of new and improved construction capable of running at high speed with the maximum output and the minimum of waste material. Although not limited in its use to any specific material, the present machine by reason of its construction is particularly well adapted for the making of bags from materials such as Cellophane and glassine and like materials which are very difficult to handle with automatic machinery.

A further object of the present invention is the provision of new and improved mechanism for partially severing the web of material prior to the final dividing of the material into bag lengths.

In the drawings accompanying this application:

Fig. 1 is a diagrammatic view illustrating an embodiment of our invention;

Fig. 2 is a side elevation of part of our improved machine;

Fig. 3 is an elevational view of the starting end of the machine;

Fig. 4 is a plan view;

Fig. 5 is a section on the line 5—5 of Fig. 3;

Fig. 6 is a section on the line 6—6 of Fig. 3;

Fig. 7 is a view taken on the line 7—7 of Fig. 2;

Fig. 8 is a view taken at right angles to Fig. 7;

Fig. 9 is a view somewhat similar to Fig. 1 of a modified embodiment of our invention;

Fig. 10 is a perspective view of a modified form of perforating mechanism;

Fig. 11 is a similar view of another modified form of perforating mechanism; and

Fig. 12 is a view of a completed bag.

Referring to the drawings in detail, 2 designates the roll of material, supported at the starting end of the machine, from which the bags are to be made. The material passes from this roll about idler rollers 4 and 6 and past paste-applying roller 8 by which paste is applied to one edge of the web. The paste pot is shown at 10 and the roller which supplies paste to the paste-applying roller 8 is shown at 12.

After the application of the paste, the web passes between forwarding rollers 14 and then beneath a tensioning roller 16, and then between perforating rollers 18 and 20, under another tensioning roller 22 and from thence to the tubing mechanism where the web is tubed.

With reference to the tensioning rollers 16 and 22, each of these rollers is mounted in a frame

comprising side members 24 which are disposed in parallel relation and secured to each other with the roller between them by rods 26. These side frame members are provided with rollers 28 and the assembly is mounted in end track plates 30 which are rigidly mounted on the machine and which extend upwardly substantially at right angles to the face of the web. It will be evident that with this arrangement each tensioning assembly is free to move freely on the end plates 10 vertically thereof.

It will be equally apparent that each tensioning assembly merely yieldingly rests by gravity upon the upper face of the moving web.

As already pointed out, a tensioning device is provided at each side of the perforating rollers to insure the right amount of tension on the web at the time the same is perforated to enable the perforating operation to be performed properly, while at the same time the tensioning arrangement being yieldingly mounted will not impose too much tension on the web, thereby enabling the web to continue its advance through the machine, without danger of premature severing of the web.

The perforating operation is only the first step in severing the bag material into bag lengths, and as will be seen is performed with the bag material in the web and without interrupting the steady advance of the web. The final step in the severing operation is performed after the web has been tubed.

The perforating mechanism of this invention is of improved and novel construction. The usual perforating mechanism comprises a serrated knife bearing against a smooth faced roller. It is difficult to maintain such arrangement in good operating condition, owing to dulling of the knife. Our construction eliminates this difficulty. Referring to Fig. 5 of the drawings, it will be seen that the perforating roller 18 is provided with peripheral circumferentially extending grooves 32. These grooves are in spaced relation along the periphery of the roller, their spacing depending upon the spacing desired of the perforations in the web. The upper roller 20 is equipped with a plate or knife 34 extending lengthwise of the roller. This plate is of course of any desired shape, depending upon the shape of the line of perforations to be made in the web. The perforated line in the web is shown at 36 in Fig. 4.

The plate 34 is chisel edged, the working edge being smooth and unserrated, and as the same rolls into contact with the grooved face of the

roller 18 it will be apparent that the web lying between the two rollers will be perforated or punctured or cut through at the high spots 38 on the roller 18 between the grooves 32.

5 The advantage of this type of perforating mechanism as compared to the usual type where a plate with a serrated edge rolls into contact with a smooth faced roller is that the un serrated chisel edge of the plate 34 of this new arrangement permits the plate to be ground from time to time without impairing its usefulness, whereas with the prior arrangement grinding soon removes the serrations entirely, necessitating replacement of the plate.

10 With the arrangement shown in Fig. 5 if it is desired to alter the spacing of the perforations in the web it is obvious that a new roller 18 with different groove spacing must be substituted for the one shown. To avoid the necessity of changing rollers every time the spacing of the perforations is to be changed, we may provide an arrangement such as illustrated in Fig. 10, for instance. In this construction the roller 40, which corresponds to the roller 18 of Fig. 5 is provided with three sets of grooved peripheral areas 42, the grooves of any one of these three sets being spaced differently from the grooves of the other two sets. The grooved areas are separated from each other by cutting away 15 part of the surface of the roller, as shown at 44. Consequently when it is desired to change the spacing of the perforations in the web being operated on, it is merely necessary that the roller 40 be shifted on its supporting shaft to bring 20 the desired set of grooves 42 into operative position. It is understood, of course, that with this form of roller the cooperating roller will be the same as the roller 20.

In the modified form of perforating mechanism shown in Fig. 11 the roller 46, corresponding to the roller 18 of Fig. 5, is provided with a set of inserted blocks 48 projecting from the face of the roller, these blocks being spaced from each other circumferentially of the roller. The face 45 of each of these blocks is provided with grooves 50 corresponding to the grooves 32 of Fig. 5, the grooves in any one block being spaced differently from the grooves in any of the other blocks. With this arrangement when it is desired to vary 50 the perforations in a web being operated on it is merely necessary to rotate the roller 46 on its shaft or in its bearing until the proper block is brought into operative position. Again, as in the case of Fig. 10, a plate which we will designate 52 is provided in the face of the upper roller 54, this plate and roller corresponding, respectively, to the plate 34 and roller 20 of Fig. 5.

After leaving the mechanism so far described the web passes through the tubing mechanism, 60 which may be of usual construction, except for two driven rollers 56 and 58, beneath which the material passes as it is tubed about the former plate 60. These rollers are driven about an axis which is oblique to the path of the traveling web, 65 these rollers tending to draw or work the material about the former plate 60, thereby materially assisting in tubing the web.

The tubed material is now advanced between feed rollers 62, and a pair of rollers 64 and 65 70 driven at the same peripheral speed as the feed rollers 62 and from thence between a pair of similar rollers 66 and 67 and another pair of rollers 68. The rollers 66, 67 and the rollers 68 are overspeeded with respect to the feed rollers 75 62 and the rollers 64, 65 and as will be brought

out hereinafter the timing of the machine is such that when the tubing in its passage through the machine reaches the point where the perforations 36 reach a position between the rollers 64, 65 and the next set of rollers 66, 67, a longitudinal tension will be suddenly applied to the tubing to pull the tubing apart along the line of perforations therein, thereby to divide the tubing into bag lengths.

5 The rollers 64 and 66 are so mounted in their 10 bearings that the tubing is not pinched except when the severing operation is to be performed, that is to say, not until the perforations 36 in the travel of the tubing have reached a point between the rollers 64, 65 and the next set of 15 rollers 66, 67.

The arrangement by which the rollers 64 and 66 are brought into cooperative relation with companion rollers 65 and 67, respectively, is shown in Figs. 7 and 8. It will be seen from 20 these two views that the upper rollers 64 and 66 are mounted for vertical bodily movement in their respective bearings, being moved downwardly toward their companion rollers by cam 70 and moved upwardly away from their companion 25 rollers by a spring 72. This bodily movement of the rollers is properly timed, as will be explained hereinafter, so that the rollers will be moved downwardly toward their companion rollers when the perforations in the tubing are in proper position for the completion of the severing operation.

After the severing or dividing operation has been completed the bag lengths are forwarded by cylinders 14 to bottoming mechanism or other mechanism for finishing.

35 Power for driving our improved machine is taken off the main drive shaft 76. This shaft is equipped with gear 78 for driving a train of gears 79, 80 and 81 which drives the cylinders or rollers 68.

The overspeeded rollers 66 and 67 are driven 40 from gear 82 on the same shaft as the gear 80, a gear 84 meshing with the gear 82 and in mesh with gear 86 on the shaft of the roller 67. This shaft also carries a gear 88 which meshes with 45 gear 89 on the shaft of upper roller 66.

50 Meshing with the gear 79 is gear 90 meshing with a gear 92. This gear 92 is mounted on shaft 94 carrying a sprocket and sprocket chain 96, the other end of this chain being carried by 55 sprocket 98. On the end of the shaft 100 carrying the sprocket 98 is a gear 102 meshing with gear 104 in turn meshing with intermediate gear 106, driving gear 108 on shaft 110. This shaft carries one end of the chain 112 of a Reeves 55 drive. The Reeves drives two gears 114 and 116. The gear 116 drives gears 118, 120 and 122 to drive the rolls 62.

The gear 120 drives gear 126 in mesh with gear 128 on the shaft of lower roll 65; the gear 128 60 meshing with gear 130 to drive the upper roll 66.

The gear 92 above referred to meshes with gear 132 to drive gear 134 on the shaft 136 of one of the cams 70 the shaft of the other cam 70 being geared to this first mentioned shaft by 65 gears 138.

On the shaft with gear 120 is a gear 124 driving intermediate gear 140 meshing with gear 142 for driving gear 144 meshing with gear 146 on the shaft of the wiping roller 58. Gear 144 70 through intermediate gear 148 and gears 150 and 152 drives the other wiping roller 56.

The perforating rollers are driven off the shaft 100 which carries a gear 154 meshing with gear 155 on the shaft 158 of the roller 18. The two 75

rollers are geared together by a pair of gears 160.

The modification illustrated diagrammatically in Fig. 9 differs from the form already described in that a roller on the end of an arm 162 is adapted to engage the perforated tube of bag material at the tensioned area to assist in dividing the same as the tube is pinched by the rollers 64, 65 and 66, 67. The arm is rocked by cam 164 on the shaft of roller 68.

10 It is to be understood that changes may be made in the details of construction and arrangement of parts within the purview of our invention.

What we claim is:

15 1. In a bag making machine, means for effecting continuous forward movement of the bag making material, a perforator in the path of the bag making material for perforating the same, and means at each side of the perforator supported yieldingly by the bag material to place a slight tension on the same as the bag material is perforated.

20 2. In a bag making machine, means for effecting continuous forward movement of the bag making material, a perforator in the path of the bag making material for perforating the same, and rollers mounted at each side of the perforator in position to rest by gravity upon the advancing bag material to be supported solely 25 thereby so as to tension the bag material during the perforating operation.

25 3. In a bag making machine, means for continuously forwarding the bag material, a perforator for perforating the same, a rigid mount 30 at each side of the perforator, a frame in each of said mounts freely movable vertically therein, and a roller carried by each of said frames and extending transversely of the machine to rest by gravity upon the advancing bag material at each side of the perforator.

40 4. A perforator for bag making material, comprising in combination a pair of rollers, one of which is provided at its periphery with a substantially non-rectilinear perforating strip, the 45 points of the cutting edge of which are equidistant from the axis of its roller, the other roller being provided with spaced grooves extending longitudinally of the roller, the face of the last mentioned roller intermediate said 50 grooves being provided with peripheral circumferential grooves, the spacing of these last mentioned grooves at any one area being different from the groove spacing of the other areas.

45 5. A perforator for bag making material, comprising in combination a pair of rollers, one of which is provided at its periphery with a substantially non-rectilinear perforating strip, the 55 points of the cutting edge of which are equidistant from the axis of its roller, the other roller being provided with grooved areas spaced 60 from each other circumferentially of the roller, the grooves of any one area being spaced differently from the grooves of the other areas.

60 6. A perforator for bag making material comprising in combination a pair of rollers, one of which is provided at its periphery with a substantially non-rectilinear perforating strip, the 65 points of the cutting edge of which are equidistant from the axis of its roller, the other roller being provided with grooved insets in the 70 face of the roller, said insets being spaced from

each other circumferentially of the roller, and the grooves of any one inset being spaced differently from the grooves of the other insets.

7. In a bag making machine wherein the bag material is advanced past perforating mechanism whereby the material is perforated at bag length intervals, means for tearing the web into bag lengths at the perforations, comprising two pairs of rollers in the path of the perforated material, means whereby one pair is overspeeded 10 with respect to the other, and means for effecting bodily movement of one roller of each pair when the perforated bag material is intermediate the two pairs of rollers, to grip the material whereby longitudinal tension will be applied to the material 15 to divide the same at the perforated area.

8. In a bag making machine wherein the bag material is advanced past perforating mechanism whereby the material is perforated at bag length intervals, means for tearing the web into 20 bag lengths at the perforations, comprising two pairs of rollers in the path of the perforated material, means whereby one pair is overspeeded with respect to the other, and a driven cam for effecting predetermined bodily movement of one 25 roller of each pair when the perforated bag material is intermediate the two pairs of rollers, to grip the material whereby longitudinal tension will be applied to the material to divide the 30 same at the perforated area.

9. In a bag making machine wherein the bag material is advanced past perforating mechanism whereby the material is perforated at bag length intervals, means for tearing the web into bag lengths at the perforations, comprising two 35 pairs of rollers in the path of the perforated material, means whereby one pair is overspeeded with respect to the other thereby to impose a sudden longitudinal tension on the perforated area of the bag material, and means operable at 40 the same time to strike the tensioned area a sharp blow thereby to divide the material into bag lengths at the perforations.

10. In a bag making machine wherein the bag material is advanced past perforating mechanism whereby the material is perforated at bag length intervals, means for tearing the web into bag lengths at the perforations, comprising two pairs of rollers in the path of the perforated material, means whereby one pair is overspeeded 45 with respect to the other thereby to impose a sudden longitudinal tension on the perforated area of the bag material, and a cam controlled arm operating in timed relation to the tensioning means to strike the tensioned area 50 a sharp blow thereby to divide the material into bag lengths at the perforations.

11. A perforator for bag material, comprising in combination a pair of driven rollers, one of which is provided at its periphery with a substantially non-rectilinear perforating strip, the 60 points of the cutting edge of which are equidistant from the axis of its roller, the other of said rollers being provided with circumferential peripheral grooves whereby the said perforating strip perforates the bag making material between said peripheral grooves as the rollers are rotated.

ADOLPH POTDEVIN.

PAUL HUNZIKER.
